COFFEE BREWER AND WARMER COMBINATION

Robert F. Ashdown, Los Angeles, Calif., assignor to Breakfast Club Coffee, Inc., Los Angeles, Calif., a corporation of California

Application February 3, 1958, Serial No. 49,478

Term of patent 3½ years

(Cl. D2—3)

FIG. 1.

FIG. 2.

The quilted pattern continues across the back of the combination and the remainder of the back is substantially plain as indicated in Figs. 2 and 3.

I claim:

The ornamental design for a coffee brewer and warmer combination, substantially as shown and described.
